UNITED STATES PATENT OFFICE

WILLIAM J. ASHER, OF COLORADO SPRINGS, COLORADO

IRONING MACHINE

Application filed March 7, 1930. Serial No. 434,113.

The present invention relates to ironing machines and particularly to ironing machines of the two rotary drum type designed and intended for the continuous ironing of articles of large size, such as sheets, blankets, and the like, as well as the general run of articles of smaller size customarily handled by laundries.

In my copending application, Serial 341-10 510, filed February 20, 1929, is disclosed an ironing machine of the two drum type and provided with two aprons, one associated with each drum, each apron serving primarily to hold an article of work in contact with 15 the cylindrical surface of the associated heated drum as the drum rotates, and the aprons acting in conjunction with each other in effecting the transfer of articles which have been acted upon by the first drum, upon one 20 side, to the second drum where they are acted up by the heated drum surface, upon the opposite side. To conduct large articles, such as sheets, blankets, and the like, from one drum to the other, the aprons are constrained to move in parallel, closely adjacent paths from a point above the first drum to a point adjacent the second drum, the articles being transferred being held between 25 the two aprons in such manner that they are delivered to the second drum entirely flat and without wrinkles. At a point adjacent the second drum, the aprons are separated, the second apron immediately passing around the second drum, and the first apron being 30 continuously backed to the first drum. Heretofore certain difficulties have been met with in effecting the dislodgement of articles of work from the first apron at the point of separation of the two aprons and the deposition 35 of such articles in proper position upon the second apron to be carried around the second cylinder, certain articles of light weight tending to adhere to the first apron and to be thrown to the floor or entangled in 40 the moving parts of the machine.

The present invention relates to means for effecting the dislodgment of articles which tend to cling to the first apron and for effecting the deposition of such articles onto 45 the second apron, thereby greatly increasing

the efficiency of the machine, permitting it to be operated at greater speeds and with fewer shut-downs, and eliminating the possibility of injury to or destruction of the articles being ironed.

The invention may be embodied in machines having widely different arrangements of rollers and aprons and may be specifically modified in each instance to suit operating conditions, without departure from its spirit and scope. In the accompanying drawings one such embodiment is set forth by way of example.

In the drawings:

Figure 1 is a rather diagrammatic longitudinal section through the complete ironing machine, showing the arrangement of 65 aprons and drums;

Figure 2 is a side elevation of one end of the machine, at which end thereof the present improvements are incorporated;

Figure 3 is a top plan view of this end of the machine partly broken away;

Figure 4 is a section on line 4—4 of Fig. 3;

Figure 5 is a section on line 5—5 of Fig. 4; 75 and

Figure 6 is a section on line 6—6 of Fig. 4.

In my copending application above referred to, the details of the machine in its entirety are described and illustrated. Inasmuch as the construction and operation of the major portion of these details have no bearing upon the present invention, a detailed description thereof need not here be set forth. All portions of the machine which 80 are pertinent to the present invention, however, will be fully described.

The ironing machine includes a frame which supports the various operating parts, this frame comprising essentially two parallel side members indicated, respectively, at 10 and 11, which side members are substantially identical in form and are rigidly secured to a base 12. Supported in the frame are two drums 13 and 14, respectively, these 90 drums being mounted to rotate about parallel axes and being spaced somewhat apart as shown in Figure 1. Associated with the drum 13, which is hereinafter designated the first drum for the reason that the articles fed 95

into the machine first make contact therewith, is an apron 15, which is endless and the width of which is substantially equal to the width of the drum. Associated with the second drum 14 is a second apron 16, also endless and having a width substantially the same as that of the second drum. A series of pressure rollers 17 disposed circumferentially of the first drum insures tight contact of the first apron with the surface of the drum, and a second series of pressure rollers 18 performs the same function with respect to the second drum and second apron. The construction and function of these pressure rollers are well known in the art.

15 Additional guide rollers are provided for guiding the two aprons along the paths outlined in Figure 1 of the drawings, and in the operation of the machine the drum or cylinders are rotated in the directions of the arrows A and B, respectively, moving in opposite directions about their axes. Each apron moves with its associated drum preferably at a very slightly greater speed than the speed limit of such drum. The aprons are brought together at a point above the first drum, indicated generally at 19 in the drawings, and pass in close parallel relationship diagonally downward to a point below the second drum, thence upwardly to a guide roller 20. After passing around this guide roller and while traveling in the general direction of the second drum 14, the aprons are separated, the point of separation being approximately indicated by the numeral 21, the two aprons following, respectively, straight diverging paths for short distances, as can be clearly seen from an inspection of Figure 4. Finally, the second apron passes over the adjacent pressure roller 18 and passes around the second drum, and the first apron passes over a smaller guide roller 22 and thence in a direction away from the second drum 14 and finally back to the first drum 13.

45 From the point 19, when the aprons come together, to the point 21, which is the point of separation, the work is tightly engaged on opposite sides by both aprons and is transported in a wrinkle-free condition by the 50 conjoint action of both aprons. Upon reaching the point of separation 21 of the two aprons, however, it is essential that the work promptly dislodge itself from the first apron and deposit itself on the second so that it may be passed around the second drum by the 55 action of the second apron without possibility of the formation of wrinkles therein. I have found that, by causing the first and second aprons to move along only slightly divergent paths for considerable distances after passing the point of separation of the aprons, and by so arranging the apron guiding means that these paths are more horizontal than vertical, the leading edge of each article of work has a much greater tendency

to separate itself from the first apron and to fall onto the second in the proper manner than when other arrangements of aprons and guide rollers are resorted to. There is a considerable tendency of the work to adhere to the first apron inasmuch as it is passed around the first drum in close and intimate contact with the first apron and under a considerable pressure of the primary set of pressure rolls. In passing around the primary drum under a considerable pressure, the various articles of work tend to become embedded in the fibrous apron, and, particularly with respect to certain types of articles, this tendency is quite pronounced, leading to the difficulties heretofore referred to. By directing the aprons after passing the point of separation in such manner that gravitational force is allowed to act on each successive article of work for a considerable period of time, it is found that by far the great majority of articles readily detach themselves from the first apron and deposit themselves in the proper manner on the second.

90 In certain instances, however, it is found that, largely because of the clinging nature of the work, some additional means is necessary to insure dislodgment of the very light articles of work from the first apron. As such an additional safeguard, I provide a 95 stream or series of jets of compressed air which are so directed as to strike the first apron tangentially as it rounds the guide roller 22 and to instantly dislodge any article clinging to its surface. Preferably, I utilize a series of parallel jets of compressed air which are caused to issue from spaced aligned ports 30 in a tubular air conduit 31 which extends transversely of the machine, the axis of the conduit being parallel to the axis of 100 the guide roll 22. The air jets are caused to impinge along substantially tangential lines upon the first apron as it passes around the guide roll 22 and to be deflected thereby, substantially as indicated by the dotted lines 105 in Figure 4, so as to approach and strike the second apron lying immediately therebelow at substantially right angles. The jets of air, therefore, not only effect dislodgment 110 of an article of work from the first apron but cause the same to flatten against the surface of the second.

115 After passing around the second drum 14, the various articles of work are removed from the surface of the drum by means of doffing knives 34 mounted upon a doffing bar 35 extending transversely of the machine and positioned immediately below a guide roller 36. The articles of work thus stripped from the rotating drum are removed from the vicinity of the doffing knives by means of a system of tapes indicated generally at T, and are carried by these tapes to a folding board. Occasionally here also, however, certain articles of the work tend to cling to 120

the second apron 16 as it passes around roller 36 instead of depositing themselves upon the moving tapes. To insure complete detachment of any such articles which have 5 a tendency to cling, I utilize at this point a second series of air streams or jets which issue in a downward direction from a series of spaced parallel ports 37 in a tubular air conduit 38. These air jets strike the outer 10 surface of apron 16 in a direction substantially tangential thereto as it passes over the roller 36 and peel off from this apron any article which tends to cling to the same, blowing the article tangentially so that it contacts 15 with the tapes and is promptly removed.

Air may be supplied under pressure to the two air manifolds 31 and 38 by any suitable means. I have found it convenient to mount a fan or blower 40 upon the frame member 20 10 of the machine and to conduct the air, which need only be under relatively slight pressure, vertically upward to an uptake 41 laid into the inner side of the frame member 10 or positioned in any suitable manner. Uptake 41 has short lateral branches indicated at 42 and 43, respectively, which branches are in communication with the adjacent ends of the two manifolds 31 and 38. Manifold 31 is secured permanently in the position 30 15 in which it is shown in the drawings, with one end permanently attached to branch 42 of uptake 41 (see Figure 6) and its other end suitably supported by a bracket 44 upon the other frame member 11 of the machine, 35 that end of the manifold remote from uptake 41 being closed, as clearly shown in Figure 6.

It is essential, however, that the upper air manifold 38 be vertically adjustable inasmuch as the guide roller 36 above which it is 40 positioned must be raised and lowered from time to time in the ordinary operation of the machine. Manifold 38 is therefore supported at its ends by arms 46 and 47 which are rigid with revoluble shaft 48 and extend 45 radially therefrom. In raising and lowering roll 36, shaft 48 is rotated by means of a worm and worm-wheel device 49 having an operating hand wheel 50. The end of manifold 38 adjacent frame member 50 11 is closed, as clearly shown in Figure 3, but that end thereof which is adjacent frame member 10 is open and is normally in registration with a similar opening formed in branch 43 of uptake 41 (see Figure 5). The 55 manifold, therefore, may be freely raised and lowered as shaft 48 is revolved in effecting adjustment of the roll 36, but, in every instance where the roll 36 is in its lowermost and operative position, the manifold 38 will 60 be connected to the source of air pressure.

It will be apparent that the invention is in nowise limited to any specific pneumatic means but that any suitable apparatus may be employed for providing air under the 65 necessary pressure and for directing the same

in streams or jets against the aprons at the desired points. I have found, however, in practice that, by the application of air currents in substantially the manner described above and illustrated in the drawings, all 70 possibility of various articles of work clinging to the respective aprons past the points at which they meet with the streams of air is wholly obviated.

Having thus described the invention, what 75 is claimed as new and desired to be secured by Letters Patent is:

In an ironing machine, in combination, a rotatable drum and an endless apron associated therewith, a second rotatable drum 80 and a second endless apron associated therewith, guide means for said aprons, including a plurality of rollers, whereby each is caused to bear against its associated drum and over a substantial area of its cylindrical surface, 85 said means also bringing the two aprons together at a point adjacent the first drum, guiding them in closely adjacent parallel paths to a point adjacent the second drum and effecting the separation of the aprons at 90 such point, the first apron returning to the first drum and the second apron passing on to the second drum, the first apron overlying the second after being separated therefrom and passing upwardly around a roller 95 of said guide means positioned above the second apron prior to returning to said first drum, and means positioned adjacent said roller for directing streams of air downwardly and tangentially against the apron moving upwardly around the same for dislodging any article of work tending to adhere to the first apron after said aprons are separated, and forcing the same onto the second apron. 100

In testimony whereof I hereunto affix my signature.

WILLIAM J. ASHER.
